UNITED STATES PATENT OFFICE

2,469,214

CENTRIFUGAL COMPRESSOR

Sanford A. Shuler, Jr., Schenectady, N. Y., assignor to General Electric Company, a corporation of New York

Application March 19, 1946, Serial No. 655,517

3 Claims. (Cl. 230—130)

1

My invention relates to a centrifugal turbomachine for pumping a fluid, particularly to a two-stage centrifugal compressor for compressible gases. The embodiment described herein is specifically intended for supercharging the cabin of a high altitude aircraft, although it may be used for supplying fluids under pressure for other purposes.

An object of my invention is to provide an improved two-stage centrifugal pump which is compact, light in weight, yet very sturdy, and easy to manufacture.

Another object is to provide an improved two-stage centrifugal compressor particularly adapted for supercharging aircraft cabins with a comparatively small volume flow of air at comparatively high pressure ratios.

Another object is to provide a multi-stage centrifugal pump arrangement having an interstage passage of good aerodynamic efficiency.

A further object is to provide an improved two-stage centrifugal pump rotor having two impellers arranged back-to-back with special sealing means for preventing leakage of fluid from the higher pressure stage to the lower.

Still another object is to provide an improved diffuser arrangement for a two-stage centrifugal compressor or pump having impellers of the type described.

Other objects and advantages will be apparent from the following description taken in connection with the accompanying drawings, in which Fig. 1 is an exploded perspective view of the components, partly in section, which make up my improved compressor; Fig. 2 is an end view of the assembled compressor; Fig. 3 is a sectional view taken on the plane 3—3 in Fig. 2; Fig. 4 is an enlarged detail view of a modification of the exit portion of the impellers and the entrance portion of the diffusers; and Fig. 5 is a still further modification of the impeller exit arrangement.

Referring now to Fig. 1, my compressor comprises a rotor 1 housed in a casing consisting of four component parts, a first casing 2 which serves to support one end bearing and defines the first stage inlet passage, a casing 3 which forms the first stage discharge scroll and a first portion of the interstage passage, a diffuser assembly 4, and a casing 5 which forms the other end bearing support and defines the remainder of the interstage passage and the second stage discharge scroll.

By reference to Figs. 1 and 3, it will be seen that the rotor comprises a shaft assembly 6 having mounted thereon a single rotor, shown at 1 in

2

Fig. 1 and comprising a hub with a radially extending web portion 7, a first stage shroud 8 and a second stage shroud 9 on opposite sides of the common web 7. Secured to members 7 and 8 are a plurality of circumferentially spaced radially extending blades 10 which define the first stage impeller flow paths. The second stage flow paths are formed by radially arranged blades 11 secured to web 7 and shroud 9. While impeller 1 bears a superficial resemblance to what is known in the art as a "double inlet impeller," it is actually two independent single inlet impellers, of materially different aerodynamic design, arranged coaxially and in back-to-back relation. It should be particularly noted that the first stage or low pressure impeller has an overall or tip diameter materially less than that of the second stage or high pressure impeller.

While the impeller 1 is disclosed in the drawings as an integral cast impeller, it will be readily appreciated by those skilled in the art that impellers of other types made by other methods of fabrication may be used. For instance, the impeller may be of the shroudless or "open" type, in which the hub and web portion and the respective blades 10 and 11 are machined from a forged disk, and portions of the stationary casting form close clearances with the edges of the blades so as to prevent leakage from the impeller flow paths. Such an open type impeller is disclosed, for instance, in U. S. Patent to Kenton D. McMahan, No. 2,380,772, issued July 31, 1945. It will be obvious that separate impellers of such a type could be mounted on a common shaft in back-to-back relation, in the manner shown in Fig. 3.

The arrangement of the inlet casing 2 may be seen by a comparison of Figs. 1, 2 and 3. Air from an inlet duct (not shown) enters the flanged inlet opening 12, into the annular inlet passage 13 and to the inlet of the first stage impeller, as indicated by the arrows 14 in Figs. 1, 2 and 3.

As can best be seen in Fig. 3, casing 2 also serves to support a first end bearing 15, which may be of any suitable type. A shaft seal assembly 16 is provided adjacent the bearing 15 to prevent lubricant entering the fluid flowing through the compressor. Further sealing effect may be provided by grooves in the casing cooperating with a portion of shaft 6 to form a labyrinth seal 17.

The periphery of the first stage impeller forms a close clearance with the inlet edges of a diffuser, formed by a radially extending plate 18 lying in a plane normal to the axis of the com-

pressor and having formed integral therewith an axially spaced parallel annular plate 19, with a plurality of circumferentially spaced radially and tangentially extending vanes 20 connecting side plate 19 to the backplate 18. Vanes 20 with the sideplates 18, 19 form a "vane type diffuser," which is well known in the art, being disclosed for instance in U. S. Patent to S. A. Moss, No. 2,157,002, issued May 2, 1939.

Casing 3, which forms the first stage discharge scroll 3a, is provided with an inwardly extending annular portion 21 which engages the outer surface of diffuser sideplate 19, and a circumferential bolting flange 22 adapted to engage a similar flange 22a on the periphery of the diffuser backplate 18. It will be apparent that the diffuser backplate 18 forms one wall of the first stage discharge scroll defined by casing 3.

As indicated in Fig. 1, the first stage discharge passage 3a increases progressively in cross-sectional area around the circumference of the first stage impeller, reaching a maximum at the section indicated by the dash-dot lines A in Fig. 1. Cross-section A may be considered to represent the exit end of the first stage discharge scroll and the beginning of the "interstage passage." The section A is seen in elevation in Fig. 3 and in edge view in Fig. 2. As may best be seen in Fig. 1, casing 3 also forms a portion of the interstage passage extending from the cross-section A and making a rather sharp 90 degree turn, ending at the section B. Cross-section B may be seen in perspective in Fig. 1, in elevation in Fig. 2, and in edge view in Fig. 3. Fluid flows through the first stage scroll 3a in the manner indicated by arrows 60.

The elongated rectangular discharge opening 23 (at section B in Fig. 1), which forms the exit of the fluid flow path defined by casing 3, cooperates with a similar opening 24 in the diffuser backplate 18.

Casing 5 forms the remainder of the interstage passage, beginning at the opening 24 in diffuser backplate 18, making a sharp 90 degree turn at 25, and having walls defining a radially inwardly extending conduit 26 which communicates with the annular second stage inlet chamber 27. Fluid discharged from the opening 23 in casing 3 flows in the direction of arrows 28, 29 (Fig. 2 and Fig. 3) to the inlet of the second stage impeller.

After flowing through the radial passages defined by impeller blades 11, the fluid is received in a second vane type diffuser formed by the common backplate 18 and a second parallel annular side plate 30, with vanes 31 (Fig. 1) therebetween. The diffuser backplate 18 forms a "backbone" lending rigidity to the whole casing assembly, while at the same time helping to define both the first and second stage diffuser passages.

The second stage discharge scroll 32 formed by casing 5 begins with a comparatively small cross-sectional area, as may be seen in the upper portion of Fig. 3, and progressively increases in area around the circumference of the second stage impeller, to a maximum at the flanged discharge opening 33, as indicated in Fig. 2. Fluid discharged from the second stage diffuser flows through the scroll 32 as indicated by the arrows 34 (Figs. 2 and 3).

It will be seen that all four casings, 2, 3, 4, and 5 cooperate to define the chamber containing the impeller 1. As shown in Figs. 2 and 3, components 3, 4 and 5 are secured together by a

common circumferential row of bolts through the flange 22 of casing 3 and similar flanges 22a and 22b on casings 4 and 5 respectively. Inlet casing 2 is secured to casing 3 by means of a separate circumferential row of bolts 35 through holes provided in a bolting flange 36. The configuration of casings 2 and 3 is carefully selected so that casing 2 may be assembled to casing 3 with the compressor inlet flange 12 in any desired angular orientation relative to casing 3. This arrangement permits the user of the compressor to readily adapt it for any desired angular relation between the compressor inlet duct (connected to flange 12) and the discharge duct (connected to flange 33). This is an important feature in aircraft installations of cabin superchargers, where there is much complex duct-work to be accommodated in a given small volume and optimum use must be made of the space available. It should be noted that this casing arrangement of my compressor permits a minimum overall axial length, the compressor inlet duct and the discharge duct being arranged in parallel, closely adjacent planes.

As may be seen in Fig. 3, end casing 5 provides a support for the left-hand shaft end bearing 37 and the shaft seal assembly 38. Casing 5 may also form a labyrinth shaft seal 39. The projecting end of shaft 6 is provided with a gear 40 adapted to be driven by any suitable means, as for instance by a gear train from the crank-shaft of a reciprocating internal combustion engine (not shown). Casing 5 is provided with a mounting flange 41, by which the compressor assembly may be bolted to a suitable support, for instance the accessory drive casing of the engine from which the compressor receives its power. The opposite end of the compressor assembly may be provided with a circumferential flange 42, to which may be secured other accessory devices, such as an electrical generator (not shown) which may have its shaft coupled to the compressor shaft by any suitable means at the fitting 43.

Attention is particularly directed to the arrangement and shape of the interstage passages in my compressor. It is well known among those skilled in the centrifugal compressor art that extremely serious energy losses can occur in the passage between the stages of a multi-stage machine unless the greatest care is taken in the design of such passages. Because of the inherent configuration of centrifugal impellers, it has been found extremely difficult to get the fluid discharged from the first stage impeller to the inlet of the second stage impeller without introducing appreciable aerodynamic losses. This is particularly true when space is at a premium and an effort is made to design a multi-stage compressor of the smallest possible overall dimensions. My invention solves this troublesome problem by an arrangement which has been found to be convenient to fabricate and assemble, yet extremely efficient aerodynamically.

As indicated above, the "interstage passage" begins at the section A and ends at the inlet to the second stage impeller. As has also been noted above, this interstage passage has a 90 degree bend between sections A and B, and a second 90 degree bend between sections B and C. Section C is indicated in perspective by dash-dot lines in Fig. 1, and is seen in edge view in Fig. 2 and in elevation in Fig. 3. Because of my use of the back-to-back impeller arrangement with a common diffuser assembly, it is necessary

to make the interstage passage of elongated or flattened cross-section at the place where it "bridges" the diffuser assembly, in order to keep the outside diameter of the complete unit to a minimum. By reference to Fig. 2, it will be seen that the interstage passage crosses over the second stage discharge scroll at a location where the latter is comparatively small in cross-section.

In order to obtain an aerodynamically efficient interstage passage, the cross-section area is progressively reduced from section A around the 90 degree bend to section B, and still further reduced around the second bend from section B to section C. Concurrently with the reduction in area from section A to section B, it can be seen in Fig. 1 that the shape of the cross-section is "squeezed down" to produce the elongated cross-section 23 having its longer dimension or "major axis" in a direction substantially normal to the plane of the bend. This transition has an important aerodynamic effect in making the rapidly flowing fluid completely fill the passage with no "boundary layer separation" of the fluid from the walls of the passage. Such separation, if it occurs, results in energy-consuming eddies adjacent the walls.

It will be appreciated by those skilled in the art of fluid mechanics that the rapidly flowing fluid will readily follow the outer surface 44, and the upper surface 45 of the passage in casing 3 (Fig. 1); but unless special precautions are taken, the fluid will tend to separate from the inner surface 46 and the lower surface 47. The danger of boundary layer separation is of course particularly acute when it is attempted to make the fluid turn a sharp corner in a small space. I have found that energy losses due to such boundary layer separation in the interstage passage of a centrifugal compressor can be reduced to a minimum and a very good efficiency obtained by the above-described reduction in cross-section area and the concurrent "squeezing down" or transitioning of the shape of the passage from the substantially square cross-section at A to a very much flattened cross-section at B. The result of reducing the passage area is of course to increase the linear velocity of the flow. The effect of progressively flattening the cross-section, as from A to B in Fig. 1, may be interpreted to result from the fact that the change in cross-section shape produces a velocity component transverse to the direction of the mean flow path. This transverse velocity component is in the direction of the lengthening dimension of the cross-section area, and has the effect of causing the fluid to tend to "hug" the downwardly curving lower surface 47, as indicated by arrow 48 in Fig. 1, and to similarly follow the inner side wall surface 46.

It is not possible to state conveniently, either verbally or mathematically, the precise interstage passage configuration required to give the best aerodynamic efficiency. However, having given the fundamental concept that it is necessary to both reduce the cross-section area as well as to change the shape of the cross-section in the manner described above, it will be readily possible for one skilled in the art to produce an efficient passage in accordance with my invention.

It will of course be understood that similar reduction in area and transition in shape are employed to cause the fluid to flow from section B to section C with a minimum of energy losses.

Because of the closely adjacent back-to-back relation of the first and second stage impellers,

it is necessary to provide sealing means for preventing fluid from leaking from the discharge of the second stage impeller back into the inlet of the first stage diffuser, which is of course at a lower static pressure. The means by which I prevent this leakage is as follows. As noted above, the first stage impeller has an appreciably smaller tip diameter than the second stage impeller. As may be seen in Fig. 3, the impeller web portion 7 is provided with a circumferential beveled surface 49, shown to an enlarged scale in Figs. 4 and 5 and extending axially and radially outward from the discharge annulus 51 of the first stage impeller to the discharge annulus 50 of the second stage impeller. In Figs. 3, 4 and 5 the common diffuser backplate 18 is represented as having a cooperating annular beveled surface 52. In Fig. 3, the cooperating surfaces 49 and 52 define a clearance space which decreases in cross-section area from the discharge annulus of the first stage impeller to the second stage impeller tip. With this arrangement, fluid discharged through annulus 51 is caused to be "rammed" into the tapered annular clearance space, so that fluid tends to flow from 51 to 50, thus counteracting the tendency of the higher static pressure produced by the second stage impeller at 50 to produce flow backwards to the first stage impeller tip 51.

If the length of the leakage flow path defined between beveled surfaces 49 and 52 is sufficient, then this clearance space may have an increasing cross-section area, carefully designed to form a diffusing passage, (see Fig. 3) so that some of the velocity energy of the fluid entering the clearance space from impeller discharge annulus 51 may be converted into static pressure, which will have a tendency to balance the static pressure in the clearance space with that at the second stage impeller tip 50. It may also be noted that with the arrangement of Fig. 3 the fluid issuing at high velocity from the second stage impeller discharge annulus 50 may produce an "ejector action" tending to entrain fluid molecules in the clearance space between surfaces 49 and 52. This ejector action combines with whatever diffusing effect may be produced in the clearance space to resist the tendency for fluid to leak backwards from 50 to 51. The above-described tendency for fluid to be "rammed" into the annular clearance space, and the "ejector action," can be increased by slightly offsetting the impeller axially relative to the diffuser inlet. This is shown in Fig. 4, in which the web 7 is offset slightly to the left, relative to the diffuser plate 18.

Fig. 5 shows a further modification of my impeller tip sealing arrangement in which the circumference of the web 7 is provided with a plurality of axially and radially extending vanes 53. These vanes serve as small auxiliary impeller blades tending to induce flow from impeller tip 51 toward the second stage impeller tip 50. This action resists the tendency of fluid to flow in the opposite direction through the clearance space between 49 and 52.

It will be seen that my invention provides an extremely compact two-stage centrifugal compressor having an improved impeller and diffuser arrangement and a novel casing structure which is aerodynamically efficient, mechanically simple to fabricate and assemble and versatile in adaptation to complex installations where space is at a premium.

While my invention has been described as a

centrifugal compressor, it will be apparent to those skilled in the art that some or all features of the invention may be equally applicable to pumps for increasing the pressure of liquids.

What I claim as new and desire to secure by Letters Patent of the United States is:

1. In a multi-stage centrifugal pump having a single inlet low pressure impeller and a single inlet high pressure impeller mounted coaxially in adjacent back-to-back relation, walls defining a first discharge scroll surrounding the low pressure impeller and having an exit directed tangentially and with a cross-section of a width substantially equal to the height thereof, walls defining an annular inlet chamber for the high pressure impeller, and walls defining an interstage passage connecting the exit of the first stage scroll to said second stage inlet chamber, said passage having adjacent the first stage exit a portion forming a first bend of substantially 90 degrees to turn the fluid discharged from said exit to a direction substantially parallel with the axis of the compressor and a second portion defining a second bend of substantially 90 degrees to conduct the fluid to said inlet chamber, said interstage passage having a cross section which gradually decreases in area and simultaneously transitions to a progressively more elongated shape with a major axis extending in a direction substantially normal to the planes of the respective bends, whereby the rapidly flowing fluid is caused to fill the passage without separation from the inside walls of the bends.

2. In a multi-stage centrifugal pump having two single inlet impellers mounted coaxially in adjacent back-to-back relation, a casing with walls defining a first stage discharge scroll surrounding one impeller and having an exit directed tangentially, said scroll exit having a cross-section of a width substantially equal to the height thereof, and casing walls forming an interstage passage connecting the first stage exit to the inlet of the other impeller, said passage including a portion adjacent the first stage exit forming a bend of substantially 90 degrees to turn fluid discharged from said scroll into a direction

substantially parallel to the axis of the compressor, the cross-section of said portion progressively decreasing in area throughout said bend and simultaneously transitioning to an elongated shape having a major axis extending in a direction substantially normal to the plane of the bend, whereby the change in cross-section area produces an increase in velocity in the direction of the fluid flow and the change in cross section shape introduces a velocity component transverse to the direction of flow so as to cause the fluid to fill the passage without separating from the inside surface of the walls thereof.

3. In a high-efficiency conduit system for conducting compressible fluids at high velocities, walls defining a conduit portion with a substantially 90° bend and a substantial concurrent deflection in a direction normal to the plane of the bend, the entrance to said 90° bend having a cross section of a width substantially equal to its height, the cross-section area of the passage progressively decreasing from the entrance throughout the bend and simultaneously transitioning to an elongated shape having a major axis extending in a direction substantially normal to the plane of the bend, whereby the change in cross-section area produces an increase in velocity in the direction of the fluid flow while the change in cross-section shape introduces a velocity component transverse to the direction of flow so as to cause the fluid to fill the passage without the occurrence of boundary layer separation along the inside surface of the convexly curved walls.

SANFORD A. SHULER, JR.
